CLAIM

The ornamental design for a computer case as shown and described.

DESCRIPTION

FIG. 1 is an exploded perspective view of the computer case of FIG. 2;

FIG. 2 is a front perspective view of a computer case, showing our new design;

FIG. 3 is an exploded front elevational view of the computer case of FIG. 2, shown with two of the elements thereof isolated and positioned side-by-side for clarity;

FIG. 4 is an exploded side elevational view of the computer case of FIG. 2, shown with three of the elements thereof isolated and positioned side-by-side for clarity;

FIG. 5 is an exploded top plan view of the computer case of FIG. 2, shown with two of the elements thereof isolated and positioned side-by-side for clarity;

FIG. 6 is an isolated rear perspective view of one element of the computer case of FIG. 2;

FIG. 7 is a front view of the computer case of FIG. 2;

FIG. 8 is an exploded perspective view of one of the elements shown in FIG. 1, to show further detail; and, FIG. 9 is an exploded perspective view of another element shown in FIG. 1, to show further detail.

Broken lines seen in the drawings depict portions of the computer case that form no part of the claimed design.

1 Claim, 9 Drawing Sheets
